COMBINED TENSION AND SCREW-DOWN CONTROL FOR STRIP MILLS

Filed Aug. 17, 1938

UNITED STATES PATENT OFFICE

2,300,990

COMBINED TENSION AND SCREW-DOWN
CONTROL FOR STRIP MILLS

Glenn E. Stoltz, Edgewood, Pa., assignor to Westinghouse Electric & Manufacturing Company, East Pittsburgh, Pa., a corporation of Pennsylvania

Application August 17, 1938, Serial No. 225,353

3 Claims. (Cl. 80—35)

My invention relates, generally, to control systems for rolling mills, and, more particularly, to a system of coordinated control for both the screw-down setting of the rolls of a strip rolling mill and the tension on the strip as it passes through such a mill.

It is common practice, in the production of steel strip, to reduce the strip by passing it through reducing roll stands, and applying tension to the strip as it passes through the roll stand. This method reduces the number of rolling passes in a single stand mill and the number of roll stands in a tandem mill necessary to produce a given reduction in the strip. The method also imparts desirable characteristics to the finished strip not otherwise obtainable.

It has also been proposed to control the amount of reduction of the strip by varying the tension on the strip in response to a thickness measuring device, thus maintaining a uniform strip thickness. Such a system is disclosed in the application of G. P. Lessmann, Serial No. 151,483, filed July 1, 1937, now Patent No. 2,268,217, issued December 30, 1941. However, the tension which is applied to a strip must have an upper limit since there is danger of breaking the strip or causing "necking" or reduction in the width of the strip if the strip tension is too great. On the other hand, if the strip tension is too small the desired strip characteristics produced by tensioning the strip will not be obtained. It is desirable that a uniform thickness of strip be produced while maintaining the strip tension within predetermined limits.

An object of my invention, therefore, is to provide a control system for a strip rolling mill which shall function to produce a strip of a predetermined thickness while maintaining strip tensions within predetermined limits.

Another object of the invention is to provide a control system for a strip rolling mill which shall function to control the screw-down setting of the reducing rolls and the tension on the strip as to produce a strip of a predetermined uniform thickness.

A further object of the invention is to provide a control system for a strip rolling mill which shall function to control the amount of tension on the strip in response to the thickness of the strip within predetermined limits of tension and to control the screw-down setting of the reducing rolls in response to variations of the strip tension beyond the predetermined limits.

Another object of the invention is to provide a control system for a strip rolling mill which

shall function to control both the tension on the strip and the screw-down setting of the reducing rolls, which shall be simple and efficient in operation and inexpensive to manufacture, install and maintain.

These and other objects and advantages of my invention will be apparent from the following detailed description taken in connection with the accompanying drawing in which:

Figure 1 is a diagrammatic illustration of a control system for a strip rolling mill embodying the principal features of my invention, and

Fig. 2 is a diagrammatic illustration of a fluid pressure operated control device which may be employed in the control system of Fig. 1.

Referring to Fig. 1 of the drawing, a tensioning device 4 is provided for applying tension to the strip 6 as it passes in the direction indicated by the arrow between the reducing roll stands 8 and 10. The tensioning device 4 is pneumatically operated and the tension applied to the strip by the tensioning device is governed by the adjustable pressure regulating valve 12. The adjustment of the valve 12 to apply the proper pressure to the tensioning device 4 is regulated in accordance with the thickness of the strip by means of a thickness gauge 14 which actuates a regulator 16 connected to control the adjustment of the regulating valve 12. The deflection of the strip 6 by the tensioning device 4 is kept within predetermined limits by controlling the speed of the driving motor 20 of the roll stand 10 by means of a regulating device 18 which may function to control the field excitation of the driving motor 20 to increase or decrease the speed of motor 20 as may be required. The operation of the tensioning device 4 under control of the adjustable regulating valve 12 in response to variations in thickness of the strip as measured by the thickness measuring device 14 and the action of regulator 16 to control the adjustment of the regulating valve 12 and the regulator 18 to control the speed of the roll stand motor 20, are fully set forth in the above referred to Lessmann patent, to which reference is made for complete explanation of the operation of the separate elements of these devices.

In order that too great a tension or too small a tension may not be applied to the strip 6 by the tensioning device 4, a screw-down device 22 is provided. This screw-down device is operable to vary the spacing of the rolls of the roll stand 8 in accordance with predetermined variations of the thickness of the strip 6 and is controlled

by the thickness-measuring device 14 through a limit switch 24 and reversing switch 26.

The tension device 4 may comprise a roller 28 supported on one end of a bell crank 30 to bear against the strip 6 deflecting the strip 6 with a transverse force, and thus tensioning the strip. The bell crank 30 may be operated by a piston 32 which, in turn, operates under fluid pressure, such for example, as air pressure in the cylinder 34, the tension applied to the strip depending upon the pressure of the air in the cylinder 34. The adjustable reducing valve 12 is connected between the air reservoir shown and the cylinder 34 to control the pressure in the cylinder 34. The pressure setting of the reducing valve 12 may be varied by varying the current flow in the solenoid 36, the air pressure delivered by the valve 12 varying inversely with the current in the coil of the solenoid 36.

The strip thickness measuring device 14 comprises generally two rotary contact members 38 which bear against the strip and which are connected in series circuit relation with one leg of a Wheatstone bridge 40, so that the variations in the thickness of the strip will vary the resistance of this leg of the Wheatstone bridge and thus vary the constant flow in the coil of a solenoid 42 connected across the bridge. The armature of the solenoid 42 actuates an arm 44 which carries control contacts for the regulator 16 which, in turn, function to govern the current flow in the coil of solenoid 36.

It is to be understood that the thickness responsive device 14 herein shown and described is merely included by way of illustration of an operative device to perform the function of measuring the strip thickness, and that the invention is not limited to this particular thickness responsive device. Any suitable thickness responsive device which will perform the desired function may be used in the combination. Such a thickness responsive device as that shown in the patent to Winne 1,969,536, issued August 7, 1934, may be used in place of the device described herein.

The deflection of the bell crank 30 by the tensioning device 4 controls the regulator 18 to vary the current flow in the field winding 46 of the motor 48 so that the speed of roll stand 10 may be increased when the deflection of the strip 6 becomes too great and decreased when the deflection of the strip becomes too small.

In order that the tension applied to the strip by the tensioning device 4 may not be too great and thus cause breakage or necking of the strip, or too small and thus cause inefficient rolling due to insufficient tension, or fail to provide the desired characteristics of the strip which are produced by the tensioning, the screw-down device 22 is varied in accordance with predetermined variations in thickness of the strip 6 to keep the tension within predetermined limits. The screw-down device 22 comprises a motor 48 which has an independent source of field excitation and which has its armature connected to be energized from a suitable source of direct current energy through the reversing switch 26. The reversing switch 26 is operated by the selective relays 50 and 52 the energization of which is controlled by a movable contact element 54, 70 which, upon predetermined deflection of the arm 44 will engage fixed contact elements 56 and 58 which are connected in circuit with the windings or relays 50 and 52, respectively.

In order that the screw-down motor 48 may 75

be "inched" or provided with predetermined limited periods of energization, a time delay relay 60 is connected in circuit with the operating relays of the reversing switch 26. The time delay relay 60 comprises an operating coil and a movable contact element 70 and a dash pot 78, the dash pot 78 providing time delay in opening and time delay in closing of the relay. The circuit for the coil of the relay 60 extends from one side of the source of energy indicated by the plus and minus signs through the conductors 62 and 64, the winding of relay 60, conductor 66, contact elements 56 and 54, conductor 68, contact element 70 of relay 60, the winding on relay 60 and conductors 72 and 74 to the other side of the source of energy. The circuit for the relay 52 of the reversing switch 26 extends from one side of the source of energy through the conductor 62, the winding of relay 52, conductor 76, contact elements 58 and 56, the conductor 68, contact elements 70, the coil of relay 60 and conductors 72 and 74 to the other side of the source of energy.

In the operation of this control system for the screw-down of roll stand 8, when the thickness measuring device 14 moves the arm 44 in response to increase in thickness of the strip 6 until the movable contact element 54 engages the fixed contact element 58, a circuit will be completed through the coil of relay 52 causing the energization of the armature of the motor 48 through the reversing switch 26 to reduce the spacing between the reducing rolls of the roll stand 8. At the time that the contact elements 54 and 58 engaged they also completed a circuit through the coil of time delay relay 60 and after a predetermined time determined by the setting of the time delay device 78, the contact element 70 will move to open circuit position to deenergize the relay 52 of the reversing switch 26 and thus deenergize the armature of the motor 48 and stop the screw-down operation. The movement of the contact elements 70 to the open circuit position will also deenergize the coil of the time delay relay 60 and after a predetermined time, depending upon the setting of the time delay device 78, the contact element 70 will again move to closed circuit position.

If, at this time the reduction of the strip has not decreased sufficiently to cause the thickness measuring device 14 to move the contact element 54 out of engagement with the contact element 58, the armature of the motor 48 will again be energized and the relay 60 will again be energized as above described. Thus, the motor 48 will receive periods of energization limited by the time delay relay 60 until the proper spacing of the reducing rolls of the roll stand 8 has been secured and the thickness measuring device 14 has moved its arm 44, so that the contact element 54 will no longer engage the contact element 58.

In a like manner the thickness gauge 14 will respond to predetermined decreases in the thickness of the strip 6 and actuate the armature of the motor 48 through the reversing switch 26 to increase the spacing of the reducing rolls of the roll stand 8.

Thus the tensioning device 4 will maintain a tension upon the strip 6 proportional to the thickness of the strip, under control of the thickness measuring gauge 14, but when this thickness increases above a predetermined amount or decreases below a predetermined

amount, the thickness measuring device 14 through limit switch 24 will adjust the reducing roll spacing of the roll stand 8 through the screw-down device 22, so that the thickness of the strip may be increased or decreased in the reducing rolls to again allow the proper range of tension to be applied to the strip 6 under the control of the thickness measuring device 14.

It will be seen that the thickness of the strip controls the pressure in the operating cylinder 34 of the tensioning device 4, and thus controls the tension on the strip 6. It will thus be seen that the screw-down may be controlled in accordance with the pressure in the cylinder 34, since this is a function of the tension on the strip 6.

In Fig. 2 I have shown a control system for the reversing switch 26 which comprises a Bourdon tube 80 connected in a suitable manner to the conduit between the regulating valve 12 and the cylinder 34 and actuating a movable contact element 54'. Fixed contact elements 56' and 58' are situated in the path of movement of contact element 54' so that the contact elements 54' and 58' will engage when the air pressure in the cylinder 34 exceeds a predetermined amount and the contact elements 54' and 56' will engage when the air pressure in the cylinder 34 becomes less than a predetermined amount. Suitable adjusting means are provided for the contact elements 56' and 58' in order to provide any desired range of movement of the contact element 54'.

The movable contact element 54' is mounted on a pivoted arm 55 which is connected to be actuated by the Bourdon tube 80 against the bias of a spring member 57. In order to provide a reasonable deflection of the movable contact element 54' at the low pressure ranges and low tension ranges, a solenoid 59 is provided. The solenoid 59 has its winding connected to a suitable source of energy through a rheostat 61 which may be actuated to provide the desired energization of the solenoid. The core of the solenoid 59 is connected to the arm 55 so that the pull of the solenoid opposes the bias of the spring 57. Thus the solenoid may be made to assist the Bourdon tube any desired amount in actuating the movable contact element 54', so that the same range of movement of the contact element 54' may be provided at low pressures as at high pressures by merely adjusting the rheostat 61.

Control circuits 66', 68' and 76' connected to the contact elements 56', 54' and 58', respectively, correspond to the corresponding control circuits 66, 76 and 68 of Fig. 1, and the device functions to control the reversing switch 26 in the manner described in detail in connection with the operation of the limit switch 24 of Fig. 1.

Thus it will be seen that I have provided a control system for a strip rolling mill which shall function to produce a strip of predetermined thickness while maintaining strip tensions within predetermined limits and which shall function to control the screw-down setting of the reduc-

ing rolls in response to variations in the strip tension beyond the predetermined limits, which shall be simple and efficient in operation, and inexpensive to manufacture, install and maintain.

5 In compliance with the requirements of the patent statutes, I have shown and described herein the preferred embodiments of my invention. It is to be understood, however, that the invention is not limited in the precise constructions 10 shown and described, but is capable of modification by one skilled in the art, the embodiments herein shown being merely illustrative of the principles of my invention.

I claim as my invention:

15 1. In a control system for a strip rolling mill, means for applying tension to a strip of material as it passes through the mill, said tensioning means comprising a pressure fluid operated means and means whereby variation of the fluid pressure will vary the tension on the strip, means for varying the fluid pressure in accordance with variations of the thickness of the strip, means for varying the spacing of the reducing rolls of the mill, and means for operating said spacing varying means in accordance with predetermined variations of the fluid pressure, said means for operating said spacing varying means comprising a fluid pressure responsive device acting against a normal bias, and means for adjusting the degree of said bias to provide a substantially constant range of movement of said fluid pressure responsive device regardless of the range of fluid pressures applied to said fluid pressure responsive device.

35 2. In a control system for a strip rolling mill, pressure fluid operated means bearing on the strip with a transverse force to subject the strip to a tension proportional to the fluid pressure acting on the pressure fluid operated means as the strip passes between adjacent work devices of the mill, regulator means for maintaining a substantially constant fluid pressure acting on the pressure fluid operated means, strip thickness responsive means for varying the regulator 40 setting to thereby vary the strip tension in response to variations of strip thickness, and means responsive to predetermined variations of strip thickness for varying the screw-down setting of the mill.

50 3. In a control system for a strip rolling mill, pressure fluid operated means bearing on the strip with a transverse force to subject the strip to a tension proportional to the fluid pressure acting on the pressure fluid operated means as the strip 55 passes between adjacent work devices of the mill, means responsive to the strip thickness for varying the fluid pressure acting on the pressure fluid operated device to thereby vary the strip tension in accordance with variations of strip thickness, and means responsive to predetermined variations in the fluid pressure acting on the pressure fluid operated means for varying the spacing of the reducing rolls of the mill.

GLENN E. STOLTZ.
